EMBALMING FLUID

Hilton Ira Jones, Wilmette, Ill., assignor to National Selected Morticians, Chicago, Ill., a corporation of the District of Columbia

No Drawing. Application October 4, 1939,
Serial No. 297,809

10 Claims. (Cl. 27—21)

The present invention relates to the embalming art. More particularly, the present invention relates to improved compositions for use in the embalming art.

The principal object of the present invention is to provide improved embalming compositions i. e. fluids for use in the preservation of dead bodies.

Other objects of the present invention will be apparent as the description hereinafter proceeds.

The present invention is predicated on the discovery that alkyl esters of dibasic aliphatic and aromatic acids are stable in the presence of ordinary embalming compositions e. g. formaldehyde, and that their addition in small amounts to embalming fluids greatly facilitates the passage of the fluids throughout the body. The esters of the dibasic acids have been found, for example, to reduce the surface tension of embalming fluids, to act as anticoagulants i. e. keep the blood liquid, and to aid in the liquefying of coagulated blood. The importance of these properties which aid in the penetration or passage of the embalming fluid through the capillaries will be apparent to those skilled in the art.

The alkyl esters suitable for use in the present invention include the esters of the lower alkyl groups, such as the methyl, ethyl, propyl, butyl, amyl, hexyl, decyl, etc. esters. The alkyl groups containing the larger numbers of carbon atoms have been found best suited for purposes of the present invention. Investigations, for example, show the ethyl esters to be better than the methyl esters, and the amyl esters, particularly the iso-amyl esters, to be better than either the methyl or ethyl esters.

The dibasic aliphatic acid groups suitable for use in the present invention include the lower aliphatic dibasic acids such as oxalic, malonic, succinic, glutaric, adipic, pimelic, suberic, sebasic, etc. acids. The properties of the acids for purposes of the present invention have also been found to improve with the increase in carbon atoms until the chain contains about 5-6 carbon atoms. Investigations, for example, show succinic acid, one of the preferred acids, to be better for purposes of the present invention than the esters formed from malonic acid.

The dibasic aromatic acid groups suitable for use in the present invention include phthalic, isophthalic, terephthalic, naphthalic, etc. The positions of the carboxyl groups around the benzene ring also affect the properties of the acids. Investigations, for example, show the ortho acid groups to be best, the para acids next and the

meta acids to be the least powerful for purposes of the present invention.

Representative esters preferred for use in the present invention include the ethyl ester of phthalic acid, the butyl ester of phthalic acid, the ethyl ester of succinic acid, the iso-amyl ester of succinic acid, etc. Ordinarily the alkyl esters of the 4-6 carbon aliphatic dibasic acids and the ortho aromatic dibasic acids are preferred.

The mono-alkyl esters of the di-basic acids are ordinarily preferred as the di-alkyl esters are relatively insoluble in most embalming fluids. Further, the alkali metal salts of the mono-alkyl esters are ordinarily preferred to the mono-alkyl esters containing a free carboxyl group. In the aromatic acids the di-alkyl esters are frequently employed particularly when the benzene ring is provided with a solubilizing group such as sodium sulfonate.

The amount of ester added to the embalming fluid ordinarily varies from 1 to 10 per cent. For most purposes the use of 1 to 5 per cent is sufficient—although the optimum amount which may vary with the type of embalming fluid being used, may readily be determined by experimental test. The following formulae will serve to illustrate the present invention:

	I	Parts by weight
30	Water	50
	Glycerine	25
	Methanol	25
	Phenol	05
35	Borax	05
	Formaldehyde (40 per cent)	200
	Mono-iso-amyl ester of succinic acid or mono-iso-amyl ester of sodium succinate	3-7

	II	Parts by weight
	Water	40
	Glycerine	20
	Methanol	40
45	Phenol	03
	Borax	07
	Formaldehyde (40 per cent)	200
	Mono-ethyl ester of phthalic acid or di-ethyl phthalate, sodium sulfonate	3-7

50 The esters for use in the present invention are stable and remain active in the presence of embalming ingredients. For example, the esters' unique anti-coagulant property is not deleteriously affected by the presence of formaldehyde, phenol, etc. Extensive investigations have shown

that the addition of small amounts of alkyl ester of dicarboxylic acid greatly facilitates the passage of the embalming fluid through the capillaries and body tissues without reducing the preserving potency of the fluid.

It will be understood that the present invention is not limited to the above illustrative examples. All modifications coming within the spirit and scope of the present invention are intended to be covered by the claims annexed hereto.

I claim:

1. An embalming fluid containing a small amount of an alkyl ester of a dibasic acid, said ester acting as a blood anticoagulant and facilitating the passage of said fluid through body capillaries and tissues during an embalming operation.

2. An embalming fluid containing a small amount of an alkyl ester of a dibasic aliphatic acid, said ester acting as a blood anticoagulant and facilitating the passage of said fluid through body capillaries and tissues during an embalming operation.

3. An embalming fluid containing a small amount of an alkyl ester of a dibasic aromatic acid, said ester acting as a blood anticoagulant and facilitating the passage of said fluid through body capillaries and tissues during an embalming operation.

4. An embalming fluid containing a small amount of an alkyl ester of a 4-6 carbon atom dibasic aliphatic acid, said ester acting as a blood anticoagulant and facilitating the passage of said fluid through body capillaries and tissues during an embalming operation.

5. An embalming fluid containing a small amount of an alkyl ester of an ortho dibasic aromatic acid, said ester acting as a blood anticoagulant and facilitating the passage of said fluid through body capillaries and tissues during an embalming operation.

6. An embalming fluid containing a small amount of ethyl succinate ester, said ester acting as a blood anticoagulant and facilitating the passage of said fluid through body capillaries and tissues during an embalming operation.

7. An embalming fluid containing a small amount of iso-amyl succinate ester, said ester acting as a blood anticoagulant and facilitating the passage of said fluid through body capillaries and tissues during an embalming operation.

8. An embalming fluid containing a small amount of an alkyl ester of phthalic acid, said ester acting as a blood anticoagulant and facilitating the passage of said fluid through body capillaries and tissues during an embalming operation.

9. An embalming fluid containing a small amount of ethyl phthalate ester, said ester acting as a blood anticoagulant and facilitating the passage of said fluid through body capillaries and tissues during an embalming operation.

10. An embalming fluid containing a small amount of an alkali metal salt of a mono-alkyl ester of a di-basic acid, said ester acting as a blood anticoagulant and facilitating the passage of said fluid through body capillaries and tissues during an embalming operation.
